UNITED STATES PATENT OFFICE.

FRED E. WHITE AND FREDERICK E. HOOPER, OF GARDNER, MASSACHUSETTS, ASSIGNEES TO CENTRAL OIL & GAS STOVE COMPANY, OF GARDNER, MASSACHUSETTS, A CORPORATION OF MASSACHUSETTS.

OIL-STOVE BURNER.

1,282,663.

Specification of Letters Patent.

Patented Oct. 22, 1912.

Application filed October 9, 1917. Serial No. 195,663.

To all whom it may concern:

Be it known that we, FRED E. WHITE and FREDERICK E. HOOPER, citizens of the United States, and residents of Gardner, Massachusetts, have invented certain new and useful Improvements in Oil-Stove Burners, of which the following is a specification.

Our present invention relates to improvements in oil burners of the type producing a white flame which burns from the side of the wick, and in which stop means are provided which will limit the upward movement of the wick under the action of the wick raiser to prevent the production of a flame of a dangerous height.

Our invention aims to provide an extremely simple, economical and durable form of wick stop which, while at all times permitting the air distributor to be readily removed will yet be operative to automatically limit the upward movement of the wick when carried into locking position as the wick is raised for lighting.

With these and other objects in view the invention includes certain novel features of construction and arrangement as well as the combination of parts hereinafter described.

In the accompanying drawing,

Figure 1 is a transverse vertical section through a burner showing the wick and air distributor in their lowered position.

Fig. 2 is a similar view showing the wick raised to the limit of movement permitted by the wick stop.

Fig. 3 is a side elevation with a portion of the outer wick tube broken away to illustrate the action of the wick raiser.

In this drawing the numerals 1 and 1^a designate respectively the inner and outer wick tubes, which are associated with an oil reservoir in the manner well understood by those skilled in the art. The numeral 2 designates the wick and 3 the perforated air distributor which may be of the ordinary or any desired construction having an annular shoulder 3^a and protruding flanges 3^b and 3^c for distributing the air to the flame in the ordinary manner. The air distributor has a central tubular sleeve 4, which slidably engages a vertical post 5 located centrally of the draft space 6, which post may conveniently be supported by a laterally projected portion 5^a secured to the inner wall of the tube 1.

The air distributor has a depending annular skirt 7 which is provided with a plurality of equi-distant recesses 7^a arranged in diametrically opposed pairs designed to engage a transverse locking bar 8 supported conveniently by having its ends secured to the wall 1 and its intermediate portion attached to the post 5. The depending portions of the skirt below the recesses are wedge-shaped or reversely inclined as indicated at 7^b so that when the distributor is lowered within the draft space contact of these inclined surfaces with the bar 8 will rotate the distributor to bring a pair of recesses in alignment with the bar. One wall of each of the recesses is made vertical or parallel with the axis of the distributor as indicated at a, while the other wall or edge is undercut to provide locking shoulders 6 which co-operate with the locking bar 8 to limit the upward movement of the wick 7^c under the action of the wick raiser in the manner hereinafter described. In order to assure the locking action we prefer in practice to incline the upper edge of the locking shoulders 6 slightly, as shown in the drawing.

From the foregoing description it will be apparent that the distributor 7 is free to be raised vertically and removed by hand from the combustion space at any time when in the position shown in Fig. 1, as the bar 8 is then in line with the narrow inlets to the recesses 7^a and there is nothing to prevent free up and down movement of the distributor.

To prevent the elevation of the distributor above a predetermined point by the raising of the wick, and hence the locking of the wick against undue upward movement, we provide means for automatically turning the distributor in the direction of the arrow, Fig. 1, as the wick is raised from the position assumed when manually placed in position. A means for accomplishing this purpose which we have devised and found effective, is shown in Fig. 3 in which the wick raiser spindle 9 is arranged at an inclination with the vertical axis of the wick tube so that at the same time that it raises and lowers the wick, it will impart a slight rotary movement thereto. The proportion of the parts is such that a very slight upward movement of the wick under the action of

the wick raiser is sufficient to cause the distributor to be rotated by its frictional contact with the upper edge of the wick to bring the shoulders *b* beneath the lower edges of the locking bar 8 and as soon as these shoulders *b* contact with the locking bar, as in Fig. 2, further upward movement of the distributor is impossible.

10 The parts are shown in locked position in Fig. 2. When the wick and distributor are again lowered the parts are automatically returned to the position shown in Fig. 1 at which time the distributor may be readily lifted out by hand.

15 We encircle the wick with a wick raising sleeve 10, which is provided with inclined rows of perforations 10^a, with which perforations the teeth of the wick raising wheels or gears 11 engage and give a slight 20 turning action as the sleeve is raised.

What we claim is:—

1. In combination, a wick tube and wick, a locking bar, an air distributor freely sup-

ported, normally, upon the said locking bar while the wick is in lowered position, means 25 for raising the wick and imparting a rotary motion thereto, and means wholly controlled by the rotary motion of the wick for locking the distributor against removal, substantially as described.

2. In combination, a wick tube having a central draft space, a wick, an air distributor removably seated in said space, a locking bar extending transversely of the draft space, said distributor having a plurality of diametrically opposed pairs of recesses, each recess having one wall made vertical and the other wall provided with a locking shoulder, the upper edge of which is inclined toward the vertical wall, converging guide edges for insuring entry of the locking bar into said recesses and means for rotating said distributor as the wick is raised, substantially as described.

FRED E. WHITE.

FREDERICK E. HOOPER.
